Patented Oct. 30, 1973

228,902

SINKING, WIGGLING, FISHING LURE

George S. Perrin, Fort Smith, Ark., assignor to Plastics Research and Development Corporation, Fort Smith, Ark.

Continuation-in-part of abandoned design application Ser. No. 124,664, Mar. 15, 1971. This application May 19, 1972, Ser. No. 255,310

Term of patent 14 years

Int. Cl. D22—05

U.S. Cl. D22—27

Fig. 1.

Fig. 2.

Fig. 3.

Fig. 4.

Fig. 5.

Fig. 6.

Fig. 7.

Fig. 8.

Fig. 9.

FIG. 1 is a side elevational view of a sinking, wiggling, fishing lure embodying my design.

FIG. 2 is a top plan view thereof.

FIG. 3 is a bottom plan view thereof.

FIG. 4 is a front elevational view thereof.

FIG. 5 is a rear elevational view thereof.

FIG. 6 is a top plan view of a modified form of the fishing lure embodying my design.

FIG. 7 is a bottom plan view of said modified form.

FIG. 8 is a front elevational view of said modified form.

FIG. 9 is a rear elevational view of said modified form.

FIG. 10 is a side elevational view of a further modified form of the fishing lure embodying my design.

FIG. 11 is a top plan view of said further modified form.

FIG. 12 is a bottom plan view of said further modified form.

FIG. 13 is a front elevational view of said further modified form.

FIG. 14 is a rear elevational view of said further modified form.

This is a continuation-in-part of my copending design application for a sinking, wiggling, fishing lure, Ser. No. 124,644, filed Mar. 15, 1971, now abandoned.

I claim:

The ornamental design for a sinking, wiggling, fishing lure, as shown and described.
